UNITED STATES PATENT OFFICE.

JEREMIAH G. DONOGHUE, OF PHILADELPHIA, PENNSYLVANIA, ASSIGNOR TO
THE LEDIG MANUFACTURING COMPANY, OF PENNSYLVANIA.

DESIGN FOR A PITCHER.

SPECIFICATION forming part of Design No. 22,214, dated February 14, 1893.

Application filed January 14, 1893. Serial No. 458,389. Term of patent 3½ years.

To all whom it may concern:

Be it known that I, JEREMIAH G. DONOGHUE, a citizen of the United States, residing in the city and county of Philadelphia, State of Pennsylvania, have invented and produced a new and original Design for a Pitcher, of which the following is a specification, reference being had to the accompanying drawing, forming part thereof.

10 The leading feature of my design for a pitcher is the lid thereof of the form of the neck and breast of a bottle.

In the drawing: A designates the body of a pitcher.

B designates the lid of the pitcher, the same being of the form of the neck C and breast D of a bottle.

I claim—

The design for a pitcher substantially as described and shown.

JEREMIAH G. DONOGHUE.
